UNITED STATES PATENT OFFICE.

JESSE A. B. SMITH, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,150,827.

Specification of Letters Patent. Patented Aug. 17, 1915.

Application filed January 15, 1914. Serial No. 312,174.

To all whom it may concern:

Be it known that I, JESSE A. B. SMITH, a citizen of the United States, residing in Brooklyn borough, in the county of Kings, 5 city and State of New York, have invented certain new and useful Improvements in Type-Writing Machines, of which the following is a specification.

This invention relates to tabulating mech-

10 anism for use on typewriting machines, and comprises improved means for selectively setting column stops to operative position, and for returning the stops to inoperative position.

15 The traveling carriage may have a rack bar mounted thereon carrying a series of column stops at letter-space intervals, said stops selectively movable into and out of the path of coöperating key-set counter- 20 stops. The rack bar may comprise vertical rack teeth on its front and rear faces for positioning and guiding the stops thereon, which stops may be yieldingly held up in in- 25 operative position by spring detents connected to the stops and projecting over the upper surface of the rack bar, said stops movable downwardly and held in operative position by said detents engaging notches in the adjacent rack teeth.

30 The stops on the rack bar may be selectively set to operative position by a stop- 35 setting blade extending over the rack bar and movable downwardly to force downward to operative position, any column stop brought beneath the blade. Said blade may be formed with a stem vertically guided and supported in a bracket, which may be mounted on the machine frame. Said blade may be depressed by means of an integral 40 finger-piece to set any column stop when the carriage has been brought to the columnar position controlled by said stop. The stop- 45 setting blade may be returned by a coil spring.

50 The column stops may be returned to in- 55 operative position by a resetting cam movable forwardly into the path of the stops. Said cam may be formed integral with a rearwardly projecting stem slidably mounted in the bracket and provided with a finger-piece for moving the cam forwardly to

operative position beneath the stops, the cam being spring returned. When the re- 60 setting cam is in operative position, the carriage may be moved from left to right, caus- 65 ing the projected stops to successively en- 70 gage the cam and thus be forced upwardly to inoperative position.

Other features and advantages will here- 75 inafter appear.

In the accompanying drawings, Figure 1 80 is a rear perspective view of the tabulating mechanism as combined with an Underwood typewriting machine. Fig. 2 is a sectional elevation showing a column stop and the 85 stop-setting blade in inoperative position. Fig. 3 is a view of the same parts, but with the stop-setting blade depressed and a stop moved thereby to operative position. Fig. 4 90 is a sectional elevation showing the reset- 95 ting device in its normal inoperative position. Fig. 5 is a view of the same parts, but with the resetting device moved to operative position and showing a stop reset thereby. Fig. 6 is a perspective view of a stop.

The rack bar 1 may be mounted on the usual traveling carriage 2, the letter-feed travel of the latter being controlled by the usual letter-feed mechanism (not shown). Vertical rack teeth 3 and 4 on the front and 95 rear faces of the rack bar are positioned at letter-space intervals and serve to position and guide a series of column stops 5. These stops 5 are preferably placed at letter-space intervals throughout the entire length of the 100 rack-bar, but for the sake of clearness of illustration some of the stops have been omitted. Each stop 5 preferably comprises front and rear vertical arms 6 and 7 guided between the rack teeth 3 and 4, and a horizontal connecting yoke or arm 8 located beneath the rack bar. Each stop 5 may be yieldingly held on the rack bar in either in- 105 operative or operative position by means of a spring detent 9, which, when the stop is in its upper or inoperative position, hooks over the upper face of the rack (Figs. 2 and 5), and when the stop is lowered to operative position (Figs. 3 and 4), said detent engages a notch 10 in the adjacent rack tooth 3.

The stops 5, when lowered as in the Fig. 3 position, are adapted to cooperate with a se-

2
ries of counter-stops 11, which may be projected into the path of the column stops 5 by keys 12 on key levers 13 extending beneath the counter-stops 11. These counter-stops, 5 which are shown as vertical bars mounted in a stationary frame 14, form a series of denominational or decimal stops selectively operable to arrest the carriage at any decimal position in a column whose location is 10 determined by the stop 5 with which the counter-stop cooperates. This operation is well understood in the art and need not be further described. It may be noted, however, that the counter-stops 11 are preferably provided with means (not shown) for releasing the carriage from the letter-feed mechanism when a counter-stop is lifted, permitting the carriage to run forward until arrested by a column stop 5 striking the projected counter-stop 11.

The stops 5 are set to operative position by means of a stop-setting blade 15, which extends forwardly over the rack 1, said blade formed integral with a stem 16 vertically supported and guided in a bracket 17, which may be secured by screws 18 to the rear face of the frame 14. When it is desired to set a stop 5 for arresting the carriage at any columnar position, the carriage 25 is brought to said position and the blade 15 is depressed by means of an integral finger-piece 19, and thereby forces downwardly the stop 5 corresponding to said position, the stop being moved from the Fig. 2 position 30 to the Fig. 3 position.

The blade 15, when released, is returned by a spring 20, which may be coiled around the stem 16, and is confined between a lug 22 on the bracket 17 and a stop pin 23 on 35 the stem 16, said stop pin also limiting the upward movement of the blade 15 by engaging a guiding lug 24 on the bracket 17. The downward movement of the blade 15 is limited by a shoulder 25 thereon, which 40 strikes the bracket 17 when the stop 5 has been lowered to such position that the detent 9 can seat in the notch 10. Any desired 45 stops 5 can thus be set, depending upon the rulings of the work-sheet or the nature of 50 the particular piece of work in connection with which the tabulating mechanism is being used.

The stops 5 may be reset to inoperative 55 position by a resetting cam 26, which may be formed integral with a rearwardly projecting stem 27 slidably mounted in the bracket 17, and movable forwardly to bring the cam 26 beneath the rack 1. The cam having been moved forwardly, as by means 60 of a finger-piece 28 to the Fig. 5 position, the carriage is moved to the right, and the projected stops 5 are thus successively brought into engagement with the cam 26 and cammed upwardly to the Fig. 5 position 65 where they are held by the detents 9 until

again set by the blade 15. The cam 26 may be returned to inoperative position by a coil spring 29 mounted on the stem 27. The movement of the resetting cam is limited in both directions by the bracket 17 as indicated in Figs. 4 and 5. 70

Variations may be resorted to within the scope of the invention, and portions of the improvements may be used without others.

Having thus described my invention, I 75 claim:

1. In a typewriting machine, the combination of a rack bar, column stops thereon, counter-stops beneath said bar, a stop setting device projecting over the rack bar, 80 said rack bar and said device relatively movable to bring any column stop beneath said device, a support in which said device is slidably mounted and guided for bodily movement downward to depress the column 85 stop into the path of a projected counter-stop, a finger-piece on the said device to depress it, and a spring to return said device.

2. In a typewriting machine, the combination of a rack bar, column stops thereon, 90 counter-stops beneath said bar, a stop setting device projecting over the rack bar, said rack bar and said device relatively movable to bring any column stop beneath said device, a support in which said device 95 is slidably mounted and guided for bodily movement downward to depress the column stop into the path of a projected counter-stop, a finger-piece on the said device to depress it, a spring to return said device, and 100 a resetting cam movable in a direction perpendicular to that in which the stop setting device moves into a position beneath the rack and in the path of the projected column stops. 105

3. In a typewriting machine and tabulating mechanism therefor, the combination with a carriage and a rack bar thereon, of a series of stops mounted on the rack bar at letter-space intervals and vertically movable into and out of operative position, and a stop-setting blade comprising a stem having a mounting in rear of the rack bar in which mounting the stem is vertically movable, said blade comprising an arm extending forwardly over the rack bar, said blade being depressible to selectively engage the stops and move them downwardly to operative position. 110

4. In a combined typewriting and tabulating mechanism, the combination of a carriage, a rack bar thereon, column stops on said rack bar, co-operating counter-stops, a stationary frame in which said counter-stops are mounted, a bracket on said frame, a stop-setting member extending over the rack bar and comprising a vertical stem mounted in said bracket, said member movable downwardly to selectively engage the stops on said rack bar and move them into position 115 120 125 130

to coöperate with the counter-stops, a coil spring mounted on said stem for returning said member, and means to limit the movement of said member in both directions.

5. In a typewriting machine and tabulating mechanism therefor, the combination with a carriage and a rack bar thereon extending in the direction of the carriage travel, stops mounted on said rack bar and movable downwardly thereon from an inoperative to an operative position, counter-stops movable into the path of the operative stops, a frame in which said counter-stops are mounted, a stop setting device comprising a stem mounted on said frame in rear of the rack bar and supported and guided for vertical movement, said device comprising an arm projecting forwardly over the rack bar into position to selectively engage the said stops, and move them downwardly to operative position, said device comprising a finger-piece for depressing it, and a spring to automatically return the device.

6. In a combined typewriting and tabulating mechanism, the combination with a carriage, of a rack bar thereon, stops on said rack bar settable to operative position, a resetting cam, a support having bearings in which the cam is slidably mounted for movement into the path of the stops, said movement of the cam being in a direction transverse to the setting movement of the stops on the rack bar, a finger-piece fixed to said cam for moving the cam to operative position, and a spring to automatically return the cam to inoperative position when the finger-piece is released, said bearings arranged to receive the pressure of the stops on the cam, the pressure being in a direction perpendicular to the direction of movement of the cam.

7. In a combined typewriting and tabulating mechanism, the combination with a carriage, of a rack bar thereon extending in the direction of the carriage travel, a series of stops mounted on the rack bar and movable downwardly to operative position, a resetting cam mounted on the machine frame in rear of the rack bar and bodily movable forwardly into the path of said stops, a stem extending rearwardly from said cam, a finger-piece on said stem for moving the cam forwardly, and a spring for returning the cam when the finger-piece is released, the reacting pressure of the stops on the resetting cam being in a direction transverse to the direction of movement of the cam, said pressure being sustained by the machine frame.

8. In a combined typewriting and tabulating mechanism, the combination with a carriage, of a rack thereon, a series of column stops on the rack, coöperating counter-stops, a frame for the counter-stops, a stop setting device mounted on said frame and

vertically movable thereon for selectively setting the column stops to operative position, and a resetting cam slidably mounted on said frame for horizontal bodily movement thereon into the path of the stops for resetting them to inoperative position, the said frame forming a support to receive the reacting pressure applied by the stops to said cam as the stops are being reset.

9. In a typewriting machine and tabulating mechanism therefor, the combination with a carriage, of a rack bar thereon extending in the direction of the carriage travel, stops on the rack bar movable in a direction transverse to that of the carriage travel from an inoperative to an operative position, a stop-restoring cam, and a support on which the cam is slidably mounted for movement transversely to the rack bar and also transversely to the direction of movement of the stops on the rack bar to bring the cam into the path of the stops for causing the stops to be returned to inoperative position by engagement with the cam during the travel of the carriage, said support arranged to receive the thrust or pressure of the stops on the cam and forming a positive means for supporting the cam during the restoration of the stops.

10. In a typewriting machine and tabulating mechanism therefor, the combination with a carriage, of a rack bar thereon extending in the direction of the carriage travel, stops settable on said rack bar by downward movement thereon from an inoperative to an operative position, counter-stops beneath the rack bar and movable upwardly into position to intercept the operative stops, a frame in which said counter-stops are mounted, a stop-restoring cam slidably mounted on said frame and normally in rear of the rack bar, said cam movable forwardly to an operative position beneath the rack bar in the path of the set stops for restoring the latter to inoperative position during the travel of the carriage, said frame forming an unyielding support for the cam to receive the pressure applied by the stops to the cam, a rearwardly projecting stem on said cam, a finger-piece on said stem to move the cam to operative position, and a coil-spring mounted on said stem and reacting between said finger-piece and said frame for restoring the cam to inoperative position.

11. In a typewriting machine and tabulating mechanism therefor, the combination with a carriage, of a rack bar thereon extending in the direction of the carriage travel, stops settable on said rack bar by downward movement thereon from an inoperative to an operative position, counter-stops beneath the rack bar and movable upwardly into position to intercept the operative stops, a frame in which said counter-

stops are mounted, and a stop-restoring cam slidably mounted on said frame and normally in rear of the rack bar, said cam movable forwardly to an operative position beneath the rack bar in the path of the set stops for restoring the latter to inoperative position during the travel of the carriage,

said frame forming an unyielding support for the cam to receive the pressure applied by the stops to the cam.
